UNITED STATES PATENT OFFICE.

PETER CHESLKA, OF CLEVELAND, OHIO.

RAILWAY-CAR BRAKE.

Application filed May 6, 1926. Serial No. 107,243.

This invention relates to new and useful improvements in railway car brakes.

The primary object of the invention is to provide a brake system for railway cars which include wheel engaging, primary brakes and track engaging, secondary or emergency brakes.

A further object of the invention is to provide emergency brakes for cars which will not only check the travel of the car, but will also function to prevent the car wheels from leaving the tracks.

A still further object of the invention is to provide improved means for actuating the above referred to emergency brakes.

Other objects and advantages of the invention will be apparent during the course of the following description.

In the accompanying drawings forming a part of this specification and in which like numerals are employed to designate like parts throughout the same,

Figure 1 is a top plan view of a railway car truck with the brake system embodying this invention properly associated therewith,

Figure 2 is a vertical sectional view of the railway car truck and shows in elevation the emergency, track engaging brakes and their actuating means, the said brakes being in their inoperative positions,

Figure 3 is a similar view to Fig. 2, but shows the emergency brake elements arranged in their operative, track engaging positions,

Figure 4 is a vertical sectional view taken upon line IV—IV of Fig. 2,

Figure 5 is a horizontal fragmentary sectional view taken upon line V—V of Fig. 2,

Figure 6 is a detail perspective view of one of the emergency brake elements actuating cam block and a fragmentary portion of its supporting element,

Figure 7 is a similar view to Fig. 4, but shows the emergency, track engaging brake elements arranged in their operative positions,

Figure 8 is a fragmentary elevational view, partly in section, of one set of the emergency brake elements,

Figure 9 is a vertical sectional view taken upon line IX—IX of Fig. 8,

Figure 10 is a horizontal sectional view taken upon line X—X of Fig. 8, and

Figure 11 is a horizontal sectional view taken upon line XI—XI of Fig. 8.

In the drawings, wherein for the purpose of illustration is shown a preferred embodiment of this invention, the numeral 5 designates a railway car carriage or pedestal frames having the journal boxes 6 mounted thereon and within which the axles 7 are journaled. These axles carry the conventional form of track engaging wheels 8, as shown.

Extending transversely of the car carriage or pedestal frame 5 is a beam 9 which includes an elliptically-shaped enlargement 10, located intermediate its ends, and the notched or cutaway portions 11 located outwardly or at each end of the elliptical portion 10. The extreme ends or extremities of the beam 9 project beyond the sides of the carriage or pedestal frames, as designated by the reference numeral 12 in Fig. 1.

The opposite sides of the carriage frame 75 are cut away at 13 in a manner to provide pockets or the like around the opposite ends of the beam 9. Bolted to the inner faces of these cutaway portions 13 are the angular guide plates 14 which are arranged with the major portions of the same extending laterally inwardly from the carriage sides and are arranged on opposite sides of and in spaced relation to the side faces of the beam 9 to form slideways or grooves. The end 85 portions of the beam 9 are illustrated in Figs. 4 and 7 as having depending therefrom the inverted M-shaped members 15 which have their sides 15^a arranged to cooperate with the side faces of the end portions of the beam 9 and the laterally inwardly extending portions of the angular guide plates 14 for forming the above referred to slideways or grooves.

Vertically, slidably mounted within each 95 one of these slideways or grooves is a block 16, best illustrated in Figs. 8 to 11 inclusive, which includes the side plates 17 held in spaced relation to each other by the centrally located spacer portion 18.

In the Figures 8 to 11, the plates 17 are illustrated as being provided with fulcrum pins 19 upon which are pivoted the apertured ears 20 of the hook-like track engaging elements 21 which have their hooked lower ends retained in spaced relation to each other by the springs 22 received at their inner ends in pockets 23 formed in the opposite sides of the spacer member 18. The upper ends of these hook-like rail engaging 110

elements 21 are clearly illustrated in Fig. 8 as being beveled at 24 to form collectively a V-shaped space.

Figure 1 clearly illustrates that there are 5 four of the blocks 15 and that they are arranged one on each side of each end portion of the beam 9. As each one of these blocks 16 carries two hook-like rail engaging elements 21, there will be two pairs of 10 such elements for each rail, as best illustrated in Figs. 2 to 4 inclusive and 7. The two blocks arranged on one or the other side of the transversely extending beam 9, and functioning to engage both of the rails, 15 are interconnected by a bar 24^a which will move with the said blocks. Figures 2, 3 and 20 7 show the bars 24 as being provided with pins 25 projecting through the vertically extending elongated slots 26 formed in the 25 opposite sides of inverted U-shaped guide members 27 which have their cross portions 28, see Fig. 1, received within the cutaway portions 11 of the beam 9 and fastened therein by the screws 29. These guide members 27 will insure uniform vertical movement of the interconnected blocks 16.

Figures 1 to 3 inclusive illustrate the centrally located, elliptical portion 10 of the beam 9 as being transversely cut away to 30 form the perpendicularly extending slot 30. Pivoted in this slot 30 are a pair of meshing, sector-shaped gears 31 which are rigidly fastened to the shaft 32 arranged on opposite sides of the beam 9 and extending 35 longitudinally thereof. These shafts 32 are held against the opposite sides of the beam 9 by the straps 33 which cooperate with the said beam for forming bearings for the shafts. These straps 33 are connected by 40 the transversely extending bolts 34 which are arranged above and below the beam 9.

Figure 6 shows one end of one of the shafts 32 and illustrates the same as being formed with a laterally extending, wedge-shaped cam 35. These cams 35 are located, 45 as shown in the various figures, in alignment with the V-shaped spaces formed by the beveled upper ends 24 of the hook-like rail engaging elements 21. The heels 35^a of the wedge-like cams 35 bear against the upper ends of the inner plates 17 of the adjacent blocks 16, as best illustrated in Figs. 1 and 4.

The flat sides of the sector-shaped gears 55 31 are illustrated as having projecting radially therefrom the gear actuating arms 36 which have connected to the outer ends thereof the rods 37. By comparing Figs. 2 and 3 and 4 and 7, it will be seen that by 60 pulling longitudinally on one or both of the rods 37, the sector-shaped gears 31 will be rotated in unison, due to their intermeshing connection, and that the shafts 32 will be rotated for causing the heels 35^a of the 65 wedge-shaped cams 35 to force the blocks

16 downwardly while the camming surfaces of the cams 35 will be forced between the beveled ends 24 of the hook-like elements 21 for causing the same to be shifted to move their lower ends toward each other 10 whereby they will engage the underneath surfaces of the rail beads or treads 38, as best illustrated in Figs. 3 and 7.

To return the blocks 16, wedge-like cams 35, gears 31, and gear actuating arms 36 to 15 their normal inoperative positions, as illustrated in Figs. 1, 2 and 4, the upper ends of the plates 17 have fastened thereto the perpendicularly extending springs 39 which have their upper ends entering the cutaway portions 13 formed in the sides of the carriage or pedestal frames 5 for being connected to the elements 40.

It will now be seen that by pulling upon the rods 37 the track engaging elements 22 will be moved from their inoperative positions above the track beads or treads 38 into their lowered, track tread engaging or clamping position. The engagement of these elements 21 with the track tread will 20 check the travel of a car equipped with this brake system and will also prevent the wheels of a car from leaving the rails or tracks.

In Figs. 2 and 3 the intermediate elliptical portion 10 of the beam 9 is illustrated as having the longitudinally extending cutaway portions 41 formed therein and communicating with the lower end of the slot 30 for forming, with this lower end, a horizontally extending slot. Figures 1 and 4 show a lever 42 pivoted in this last mentioned slot and having the links 43 connected to the opposite ends thereof. These links have their outer ends pivotally connected to rods 44 which pass through transversely extending bars 45 and are prevented from moving relative thereto by the stop collars 46. These bars 45 have mounted upon their outer ends the wheel tread engaging brake shoes 47 which are supported by the chain links 48 connected to the carriage or frames 5.

It will now be seen that by pulling upon one of the rods 44, the brake actuating bar 45 directly connected thereto will be moved for applying the brake shoes 47 fastened to the opposite ends of this bar. This movement of the bar 45 will cause the link 43 connected thereto to be shifted for rocking 120 the lever 42 to move the remaining link 43, connected to its opposite end, in a manner to shift the second brake shoe bar 45 for applying the second set of brake shoes 47.

It is to be understood that the form of 125 this invention herewith shown and described is to be taken as a preferred example of the same, and that various changes in the shape, size, and arrangement of parts may be resorted to without departing from the 130

spirit of the invention or the scope of the subjoined claims.

Having thus described the invention, I claim:

5. 1. In apparatus of the type described, the combination with a car carriage having rail engaging wheels, of a sliding block carried by each side of said carriage, means for interconnecting said blocks for causing them 10 to move in unison, a pair of rail gripping elements pivotally carried by each of said blocks, and means for sliding said blocks downwardly and at the same time pivoting said elements into their rail gripping positions.

2. In apparatus of the type described, the combination with a car carriage having rail engaging wheels, of a beam extending transversely of said carriage, blocks slidably carried by the sides of said carriage and arranged on opposite sides of the end portions of said beam, a pair of rail gripping elements pivotally carried by each of said blocks, and mechanism for slidably moving 25 all of said blocks downwardly in unison and at the same time pivoting said elements into their rail gripping positions.

3. In apparatus of the type described, the combination with a car carriage having rail 30 engaging wheels, of a beam extending transversely of said carriage, blocks slidably carried by the sides of said carriage and arranged on opposite sides of the end portions of said beam, a pair of rail gripping elements pivotally carried by each of said blocks, mechanism for slidably moving all of 35 said blocks downwardly in unison and at the same time pivoting said elements into their rail gripping positions, said means including a shaft journaled on each side of 40 said beam and extending longitudinally thereof, a wedge-shaped cam carried by each end of each shaft and arranged to engage the blocks and rail gripping elements, and 45 means for rocking said shafts in unison.

4. In apparatus of the type described, the combination with a car carriage having rail 50 engaging wheels, of a beam extending transversely of said carriage, blocks slidably carried by the sides of said carriage and arranged on opposite sides of the end portions of said beam, a pair of rail gripping elements pivotally carried by each of said blocks, mechanism for slidably moving all 55 of said blocks downwardly in unison and at the same time pivoting said elements into their rail gripping positions, said means including a shaft journaled on each side of 60 said beam and extending longitudinally thereof, a wedge-shaped cam carried by each end of each shaft and arranged to engage the blocks and rail gripping elements, means for rocking said shafts in unison, said last 65 mentioned means including a pair of intermeshing sector gears mounted one on each

of said shafts, and an arm extending radially from each of said sector-shaped gears.

5. In apparatus of the type described, the combination with a car carriage having rail 70 engaging wheels, of a sliding block carried by each side of said carriage, a pair of rail gripping elements carried by each of said blocks and adapted to pivot toward and away from each other in vertical planes extending at right angles to the vertical planes 75 of said rail engaging wheels, and a pivoted wedge-like cam positioned at each side of said carriage and adapted to pivot in planes extending vertically at right angles to the rail gripping elements for engaging the 80 sliding blocks and the upper ends of said elements to move the blocks downwardly and at the same time pivot said elements into their rail gripping positions.

6. In apparatus of the type described, the combination with a car carriage having rail 85 engaging wheels, of a sliding block carried by each side of said carriage, a pair of rail gripping elements carried by each of said blocks and adapted to pivot toward and away from each other in vertical planes extending at right angles to the vertical planes 90 of said rail engaging wheels, a pivoted wedge-like cam positioned at each side of 95 said carriage and adapted to pivot in planes extending vertically at right angles to the rail gripping elements for engaging the sliding blocks and the upper ends of said elements to move the blocks downwardly and at the same time pivot said elements into 100 their rail gripping positions, and means for returning said blocks into their normal inoperative positions.

7. In apparatus of the type described, the combination with a car carriage having rail 105 engaging wheels, of a sliding block carried by each side of said carriage, a pair of rail gripping elements carried by each of said blocks and adapted to pivot toward and away from each other in vertical planes extending at right angles to the vertical planes 110 of said rail engaging wheels, a pivoted wedge-like cam positioned at each side of said carriage and adapted to pivot in planes extending vertically at right angles to the rail gripping elements for engaging the 115 sliding blocks and the upper ends of said elements to move the blocks downwardly and at the same time pivot said elements into their rail gripping positions, means for sliding said blocks into their normal inoperative positions, and means for pivoting said rail gripping elements into their inoperative positions as the blocks are returned to their normal inoperative positions.

8. In apparatus of the type described, the combination with a car carriage having rail 120 engaging wheels, and a transversely extending beam carried thereby, of a pair of horizontally movable bars, a brake shoe carried 125

by each end of each bar and adapted to be moved into engagement with the treads of said rail engaging wheels, a lever pivotally carried by said transverse beam, links pivotally connected to the opposite ends of said lever and to the brake carrying bars, and a rod connected to each of said bars, whereby

a pull upon one of said rods for moving a bar to apply the brake shoes carried by the latter will cause the links and lever to actuate the remaining bar for applying the brake shoes carried by the same. 10

In testimony whereof I affix my signature.
PETER CHESELKA.
